UNITED STATES PATENT OFFICE.

MATTHEW L. HOYT, OF LITTLE FALLS, NEW YORK, ASSIGNOR TO D. H. BURRELL & COMPANY, OF LITTLE FALLS, NEW YORK.

SHAFT-MOUNTING FOR CENTRIFUGAL MACHINES.

No. 850,477.

Specification of Letters Patent.

Patented April 16, 1907.

Application filed January 30, 1907. Serial No. 364,818.

To all whom it may concern:

Be it known that I, MATTHEW L. HOYT, a citizen of the United States, residing at Little Falls, in the county of Herkimer and 5 State of New York, have invented a new and useful Improvement in Shaft-Mountings for Centrifugal Machines, of which the following is a specification.

This invention relates to the mounting of 10 upright shafts or spindles which rotate at a high speed and in which the load is applied to the shaft or spindle above the bearings—as, for instance, in that class of centrifugal cream-separators in which the bowl or drum 15 is mounted upon the upper end of the shaft or spindle. In this class of machines it is very difficult to balance the bowl or drum so correctly that it will run without vibration at the high speed at which such machines are 20 operated, and various devices have been used for allowing the shaft or spindle to center itself to a certain extent and to run approximately in the natural axis of rotation or axis of gravity. None of these devices has 25 been entirely satisfactory; and the object of this invention is to produce such a self-centering shaft-mounting which is simple in construction, easy to assemble, durable, and very efficient in allowing the self-centering 30 action which is necessary to cause the bowl or drum to run without vibration although more or less out of balance.

In the accompanying drawings, Figure 1 is 35 a sectional elevation of a centrifugal cream-separator provided with this improved shaft-mounting. Fig. 2 is a vertical section of the self-centering supporting-bearing, the restraining-bearing, and adjacent parts on an enlarged scale. Fig. 3 is a vertical section of 40 the lower bearing on an enlarged scale. Fig. 4 is a horizontal section through the self-centering supporting-bearing in line 4-4, Fig. 2. Fig. 5 is a horizontal section through the restraining-bearing in line 5-5, Fig. 2. Fig. 6 is 45 a sectional elevation showing a modified construction of the self-centering supporting-bearing.

Like letters and numerals of reference refer to like parts in the several figures.

50 A represents the bowl or drum of a centrifugal cream-separator, and B the upright shaft or spindle, to the upper end of which the bowl or drum is secured and which is ro-

tated by any suitable mechanism—for instance, as shown, by a worm-wheel C, a worm c, a hand-operated wheel D, and a pinion d.

E represents the stationary frame in which the shaft is supported near its upper end and below the bottom of the bowl in a self-centering bearing F, which permits the shaft to change its position automatically in seeking its natural axis of rotation. The shaft runs at or near its lower end in a bearing or bushing G, which holds the shaft in position against lateral displacement, but does not support the shaft. The weight of the shaft, bowl, and contents is supported by the upper self-centering supporting-bearing F, and not by the lower bearing or bushing G. The point of support is therefore located considerably nearer the center of gravity of the bowl than in machines in which the weight is supported by a step-bearing at the lower end of the shaft, and this arrangement assists materially in steadyng the shaft and bowl.

In addition to the upper self-centering supporting-bearing F and the lower bearing G the shaft-mounting comprises a restraining bearing or bushing H, which is located near the supporting-bearing F, preferably below the same. The bore of this restraining-bearing is so much larger in diameter than the shaft that this bearing is not touched by the shaft in the positions which the shaft assumes in the ordinary variations of running. When the shaft, however, wobbles, gyrates, or moves sidewise beyond its ordinary range of positions, it comes in contact with the bearing or bushing H, and the latter then restrains the further sidewise movement of the shaft and confines the shaft to its permissible range of movement. This restraining-bearing is yieldingly held in its normal position by a spring device of any suitable construction, so arranged that the bearing will yield sidewise to a certain extent when struck by the shaft and will be returned to its central or normal position as the disturbing force expends itself.

The self-centering supporting-bearing F (represented in Figs. 1, 2, and 4) is constructed as follows: 10 represents the portion of the stationary frame E in which this bearing is supported, and 11 represents the casing of the bearing, which is seated in the frame and

provided with a screw-cap 12. 13 represents a lower supporting-ring which rests movably in the cavity 14 of the casing. This cavity is spherical in form, and the ring is 5 rounded at its peripheral face, so that it can tilt in the cavity. 15 represents antifriction-balls which rest upon the ring 13, and 16 represents a thin spacing-ring which has openings for the balls and rests loosely upon an an- 10 nular shoulder 17 in the casing 11, so that it can move freely on this shoulder in following the balls. 18 represents an upper supporting-ring which rests upon the balls and upon which the shaft rests by a neck 19, which is 15 spherical in form and capable of tilting in the upper supporting-ring 18. The central openings in the supporting-rings 13 and 18 and in the spacing-ring 16 are made so much larger than the shaft that the latter can move 20 freely in a sidewise direction in these openings. The two supporting-rings 13 and 18 are preferably made alike, as shown, and each is made alike on its upper and lower sides, so that in assembling the bearing either ring can 25 be used as the lower ring and each ring can be arranged either side up. The central openings of these supporting-rings are beveled or tapered inwardly from both sides to contact with the spherical neck 19 of the shaft. The 30 screw-cap 12 of the casing confines the loose parts in the casing and is sufficiently large to permit of the necessary free movement of these parts.

The weight of the shaft and the parts sup- 35 ported thereby falls, primarily, upon the upper supporting-ring 18 and is transmitted by the balls to the lower supporting-ring 13, which in turn rests on the casing 11, the latter being supported by the stationary frame. 40 The upper supporting-ring 18 rotates with the shaft and on the balls, which in turn revolve about the shaft on the lower supporting-ring. The shaft is enabled to tilt in the self-centering supporting-bearing F by 45 means of the spherical neck 19, which tilts in the upper ring 18, and the bearing is enabled to tilt in its stationary support by means of the lower ring 13, which tilts in the spherical cavity of the casing or other support. These 50 two spherical joints, one between the shaft and the bearing and the other between the bearing and its stationary support, enable the bearing to always assume a position in which it stands at right angles to the natural 55 running axis of the shaft, and the shaft is thereby enabled to rotate freely about its natural running axis or axis of gravity. If the shaft moves sidewise in seeking the natural axis of rotation, the upper supporting- 60 ring 18 moves sidewise on the balls, and the latter may move sidewise on the lower supporting-ring 13 until the shaft runs without vibration. The upper supporting-bearing F forms in this manner a self-centering support 65 for the shaft, and as this bearing is located

very near the bottom of the bowl the variations or vibrations caused by an unbalanced bowl are applied to this bearing directly and without causing the shaft to spring, and the shaft is enabled to quickly assume that position in which the bowl runs steadily and without vibration. The necessity of balancing the bowl correctly, which is a matter of considerable difficulty and expense, is thereby avoided.

For comparatively light or small centrifugal separators—for instance, cream-separators which are operated by hand—a supporting-bearing with a single row of balls gives satisfactory results; but for larger machines— 70 for instance, those which are operated by power—it is often desirable to use a bearing with two rows of balls, as represented in Fig. 6. In this construction an intermediate supporting-ring 20 is interposed between the 85 upper row of balls 21, on which the upper supporting-ring 18 rests, and the lower row of balls 22, which rest on the lower supporting-ring 13. The spacing-ring 23 of the lower row of balls rests on the shoulder 24 90 in the casing 11, and the spacing-ring 25 of the upper row of balls rests on a collar 26, which may rest on a shoulder 27 in the casing outside of and above the lower spacing-ring. This collar is held from turning 95 by a screw 28 or other suitable means. Oil may be supplied to the self-centering bearing in any suitable manner—for instance, by a pipe 29.

The lower bearing or bushing G, which is 100 represented on an enlarged scale in Fig. 3, is supported in the lower portion 30 of the stationary frame in any suitable manner—for instance, by a housing 31, which is provided with an internal shoulder 32, on which 105 the bearing rests by a collar 33, the housing being prevented from turning by a screw 34 or other suitable means. This lower bearing or bushing holds the lower end of the shaft against lateral displacement, but does 110 not support the load.

The restraining-bearing H may be yieldingly held in position in the frame by a ring 35 of india-rubber or by any other suitable or well-known spring or system of springs. 115 The internal diameter of this bearing is so large that the shaft can freely move in the same sidewise without coming in contact therewith so long as the displacement of the shaft does not exceed the permissible range 120 of variation. When this is exceeded, the lateral sway of the shaft is arrested by this bearing, and dangerous wobbling or gyrating of the shaft is thereby avoided.

The sidewise movement of the upper portion of the shaft and of the bowl mounted thereon which occurs in the self-centering action is comparatively small and takes place about the lower bearing as a pivotal point and is permitted partly by reason of the 130

slight unavoidable play between the lower bearing and the shaft and the natural flexibility of the shaft.

I claim as my invention—

1. A mounting for a vertical shaft comprising a self-centering supporting-bearing arranged near the upper end of the shaft, a load carried by the shaft above said supporting-bearing, and a bearing arranged near the lower end of the shaft, the self-centering supporting-bearing carrying the load and permitting the upper portion of the shaft to move sidewise in self-centering, and the lower bearing holding the lower portion of the shaft against sidewise movement, substantially as set forth.

2. A mounting for a vertical shaft comprising a self-centering ball-bearing arranged near the upper end of the shaft and supporting the load, a load attached to the shaft above said supporting-bearing, and a lower bearing which holds the lower portion of the shaft against sidewise movement without supporting the load, substantially as set forth.

3. A mounting for a vertical shaft carrying the load at its upper end, said mounting comprising a self-centering supporting-bearing which is arranged near the upper end of the shaft and carries the load, and a restraining-bearing having a bore which is larger in diameter than the shaft and permits the latter to move freely sidewise within the ordinary range of positions, but restrains excessive sidewise movement of the shaft, substantially as set forth.

4. A mounting for a vertical shaft carrying the load at its upper end, said mounting comprising a self-centering supporting-bearing which is arranged near the upper end of the shaft and carries the load, a restraining-bearing having a bore which is larger in diameter than the shaft and permits the latter to move freely sidewise within the ordinary range of positions but restrains excessive sidewise movement of the shaft, and a bearing which holds the lower portion of the shaft against sidewise movement without supporting the load, substantially as set forth.

5. A mounting for a vertical shaft carrying the load at its upper end, such mounting comprising a self-centering ball-bearing which supports the load and is arranged near the upper end of the shaft below the load, said supporting-bearing being capable of tilting in its support and the shaft being capable of tilting in the bearing and of moving sidewise in finding its natural axis of rotation, substantially as set forth.

6. In a self-centering shaft-mounting, the combination of a stationary support having a spherical cavity, a lower supporting-ring capable of tilting in said cavity, balls resting on said ring, an upper supporting-ring resting

on said balls and capable of sidewise movement thereon, and a shaft having a spherical neck by which it can tilt in said upper supporting-ring, substantially as set forth.

7. In a self-centering shaft-mounting, the combination of a stationary support having a spherical cavity, a lower supporting-ring capable of tilting in said cavity, balls resting on said ring, a spacing-ring for said balls resting in said stationary support and capable of lateral movement therein, an upper supporting-ring resting on said balls and capable of lateral movement thereon, and a shaft resting on said upper supporting-ring, substantially as set forth.

8. In a self-centering shaft-mounting, the combination of a stationary support having a spherical cavity and above the same an internal shoulder, a lower supporting-ring capable of tilting in said cavity, balls resting on said ring, a spacing-ring for said balls resting on said shoulder and capable of lateral movement thereon, an upper supporting-ring resting on said balls and capable of lateral movement thereon, and a shaft capable of tilting in said upper supporting-ring and capable of sidewise movement in said lower supporting-ring, substantially as set forth.

9. In a self-centering shaft-mounting, the combination of a stationary support having a spherical cavity, a lower supporting-ring capable of tilting in said cavity, balls resting on said ring, and an upper supporting-ring resting on said balls and capable of lateral movement thereon, said rings being alike in form and interchangeable, substantially as set forth.

10. In a self-centering shaft-mounting, the combination of a stationary support having a spherical cavity, a lower supporting-ring capable of tilting in said cavity, balls resting on said ring, and an upper supporting-ring resting on said balls and capable of lateral movement thereon, each of said rings being of the same form on its upper and lower sides and reversible, substantially as set forth.

11. In a self-centering shaft-mounting, the combination of a stationary support having a spherical cavity, a lower supporting-ring capable of tilting in said cavity, balls resting on said ring, and an upper supporting-ring resting on said balls and capable of lateral movement thereon, each of said rings being reversible and both rings being alike in form and interchangeable, substantially as set forth.

Witness my hand this 25th day of January, 1907.
